UNITED STATES PATENT OFFICE.

LOUIS FINIELS, OF NEW ROCHELLE, NEW YORK.

ATTACHMENT FOR BROOMS OR BRUSHES.

SPECIFICATION forming part of Letters Patent No. 665,632, dated January 8, 1901.

Application filed May 10, 1900. Serial No. 16,118. (No model.)

To all whom it may concern:

Be it known that I, LOUIS FINIELS, a citizen of the United States, and a resident of No. 148 Elm street, New Rochelle, county of West Chester, and State of New York, have invented 5 certain new and useful Improvements in Attachments for Brooms or Brushes, of which the following is a specification, reference being had to the accompanying drawings, forming a part thereof, in which similar letters of reference indicate corresponding parts.

This invention relates to an improvement in attachments for brooms and brushes; and the object thereof is to provide a device of 15 this character which is adaptable for use in combination with brushes and brooms of ordinary construction and which embodies a scraper and a fine brush portion, whereby when the device is attached to the broom or 20 brush an efficient article is provided which is adaptable for use in the operation of cleaning several different kinds of material.

The invention will be hereinafter fully described, and specifically set forth in the annexed claims.

In the accompanying drawings, forming part of this specification, Figure 1 is a side elevation of my improved attachment, showing the same in connection with a whisk-broom; Fig. 2, an edge elevation; and Fig. 3, 30 a longitudinal elevation, partly in section, showing a modified construction applicable for an ordinary bristle clothes-brush.

In the practice of my invention as shown 35 by Figs. 1 and 2 of the drawings I employ an upper resilient band A and a lower resilient band B, both bands being composed, preferably, of rubber; but other suitable flexible material may be employed, if desired. Bridging these two bands on one side is a flexible base-plate C, having a series of teeth or projections c extended over its entire outer surface and preferably formed integral therewith. These teeth act as scrapers for removing 40 mud or other hardened substances not susceptible of being removed by the ordinary whisk-broom or bristle brush. The opposite side of the device embodies a base sheet or plate D, which carries upon its outer surface 45 a brush d, which is preferably of very fine quality, or of a quality differing widely from the ordinary brush to which the device is at-

tached, whereby it may be employed as a means for brushing very fine fabrics.

The device may be slightly modified in form 55 to make it adaptable for attachment to various kinds of clothes-brushes. For instance, as shown by Fig. 3 of the drawings, the attachment embodies a rubber band E, having the rubber base-sheets F and G formed in 60 integral therewith and stretched over the back h of the ordinary bristle clothes-brush H, the band E tightly encircling the bristle-body of the brush to keep the device in place. In this structure the teeth c' are extended over 65 the surface of the base F to cover one end portion of the brush-back, and the fine brush d' is attached to the surface of the base-sheet G to cover the opposite end portion of the brush-back.

In the operation and use of the device it is readily stretched over and attached to a suitable brush by reason of the resilient nature of its component parts, and it is obvious that a handy and effective device is provided for 75 cleaning and brushing various kinds of materials.

Having thus described my invention, what I claim as new, and desire to secure by Letters Patent, is—

1. An attachment for brushes and brooms embodying oppositely-located base-sheets, carrying respectively a plurality of scrapers, and a fine brush, and means for fastening 80 said attachment to brushes and brooms substantially as illustrated and described.

2. In a device for brushing and cleaning fabrics, the combination of a scraper embodying a plurality of teeth, a fine brush, and oppositely-located base-sheets, carrying respectively the said brush and scraper, with means 85 embodying resilient bands, for encircling brushes and brooms, and affording facility for attaching the said device thereto, all substantially as illustrated and described.

In testimony that I claim the foregoing as my invention I have signed my name, in presence of two witnesses, this 26th day of April, 1900.

LOUIS FINIELS.

Witnesses:

JOHN F. CONDON,
FRANCIS H. DAVIS.
